INVENTOR
FRANK WRIGHT

BY *Fetherston Haugh & Co.*
ATTY'S

UNITED STATES PATENT OFFICE.

FRANK WRIGHT, OF BLAIRMORE, ALBERTA, CANADA.

SECURITY SHEATH HINGE AND DOOR FASTENING.

1,340,430.

Specification of Letters Patent.

Patented May 18, 1920.

Application filed November 28, 1919. Serial No. 341,043.

To all whom it may concern:

Be it known that I, FRANK WRIGHT, a subject of the King of Great Britain, a resident of the town of Blairmore, Province of 5 Alberta, Dominion of Canada, have invented certain new and useful Improvements in Security Sheath Hinge and Door Fastenings, of which the following is a specification.

- 10 This invention relates to improvements in security sheath hinge and door fastenings, and the objects of the invention are to render the hinge and door fastener burglar proof by preventing the removing of the same 50
15 when the door is closed, to provide means whereby the hinge or fastening means proper form a cover member for screws or other like means whereby the hinge or fasteners are attached to the door, and generally to adapt the several parts to better 20 perform the functions required of them.

With the above and other objects in view, the invention consists essentially of the improved construction particularly described 25 and set forth in the following specification and accompanying drawings forming part of the same.

In the drawings:

Figure 1 is a perspective view of one form 30 of my improved hinge.

Fig. 2 is a longitudinal section of the same.

Fig. 3 is a front elevation of the hinge member.

Fig. 4 is a perspective view of one of the 35 tubular members showing the tongue on the end thereof.

Fig. 5 is a transverse section of the tubular member.

Like characters of reference refer to like 40 parts in the several figures.

Referring to the drawings: The tubular members 45 taper toward one end and are provided at the smaller end with tongues 46. The hinge members 47 taper toward that end remote from the hinge pin and are each 45 provided with a slot 48. The tubular members 45 are secured to the door, door frame, or to two adjacent portions of a door, by bolts which pass through the orifices provided in the tubular members. 50

The door is held in position by inserting the hinge members 47 into the tubular members and then bending the tongue 46 to engage with the slots 48.

It will thus be evident that the tongue 55 forms a locking means between the hinge and tubular member.

From this description it will be seen that I have invented a burglar proof hinge in which the hinge member cannot be removed 60 when the door is closed.

What I claim as my invention is:

A device of the class described, comprising a tubular tapered member designed to be secured to a door and having a tongue, a 65 hinge member slidably engaging the tubular member and provided with a slot, means for securing the tubular member to the door, the said means under-lying the hinge member, the tongue being designed to be bent 70 over and engage with the slot, as and for the purpose specified.

In witness whereof I have hereunto set my hand in the presence of two witnesses.

FRANK WRIGHT.

Witnesses:

JOSEPH E. GILLIS,
ARTHUR J. KELLY.
